(57) **CLAIM**

The ornamental design for a front bumper panel, as shown and described.

DESCRIPTION

FIG. 1 is a front perspective view of a front bumper panel in accordance with the present invention;

FIG. 2 is another front perspective view of the front bumper panel of FIG. 1;

FIG. 3 is a rear perspective view of the front bumper panel of FIG. 1;

FIG. 4 is another front perspective view of the front bumper panel of FIG. 1;

FIG. 5 is a front elevation view of the front bumper panel of FIG. 1;

FIG. 6 is a top plan view of the front bumper panel of FIG. 1; and,

FIG. 7 is a right side elevation view of the front bumper panel of FIG. 1, wherein a left side elevation view is a mirror image thereof.

The surface ornamentation of FIGS. 1 to 5 is for illustrative purposes only and forms no part of the claimed design.
